UNITED STATES PATENT OFFICE.

J. V. B. CARTER, OF DETROIT, MICHIGAN, ASSIGNOR TO DETROIT STOVE-WORKS, OF SAME PLACE.

DESIGN FOR COOKING-STOVE.

Specification forming part of Design No. 7,722, dated September 1, 1874; application filed July 24, 1874.
 [Term of Patent 7 years.]

To all whom it may concern:

Be it known that I, JOHN V. B. CARTER, of Detroit, in the county of Wayne and State of Michigan, have invented a Design for Cooking-Stoves, of which the following is a specification:

The nature of my design is fully represented in the accompanying photographic illustration, to which reference is made.

A represents the body of the stove, which may have a reservoir and hot-closet under an extension-top, as shown, or they may be omitted, as in other square-top stoves.

One of the prominent features of my design is the front plate, which extends the full length of the fire-box, which is made without the usual pockets. The front plate is also provided with an illuminated door, *a*. The fire-door *c* and oven-door *d* are molded with bulging panels, as shown, with deep, bold mold-

ings at the edges, faced with a molding simulating a chain of square links interlaced at their corners. The moldings at the edges of the plates are of the same character as those of the doors, without, however, the chain facing. The front plate extending entirely across the front end of the stove makes it appear wider than it really is in the body in looking at it from the front.

What I claim as my invention is—

The design for a cooking-stove, consisting of the front plate *B*, made without the usual panels or pockets, and provided with the illuminated door *a*, and the side plates *C*, with the doors *c d e*, having bulging panels, substantially as represented and set forth.

JOHN V. B. CARTER.
